UNITED STATES PATENT OFFICE.

EMERSON L. CLARK, OF LAKEWOOD, OHIO, ASSIGNOR TO NATIONAL CARBON COMPANY,
OF CLEVELAND, OHIO, A CORPORATION OF NEW JERSEY.

COMPRESSION-RHEOSTAT.

1,154,377.

Specification of Letters Patent. Patented Sept. 21, 1915.

Application filed March 17, 1913. Serial No. 754,708.

To all whom it may concern:

Be it known that I, EMERSON L. CLARK, a citizen of the United States, residing at Lakewood, in the county of Cuyahoga and 5 State of Ohio, have invented a certain new and useful Improvement in Compression-Rheostats, of which the following is a full, clear, and exact description.

My invention relates to that type of rheo- 10 stats commonly known as compression rheo- stats.

One of the objects of this invention is to secure a compact rheostat of large capacity composed of a number of similar units 15 which may be operated from a single point.

Another object is to secure means for transmitting uniform and definite pressure which will not be altered by temperature changes.

20 Another object is to secure a resistance element which is self-alining.

Another object is to obtain a draft or chimney effect through the rheostat to increase its capacity.

25 Further objects will appear in the appended description.

Referring to the drawings, Figure 1 is the top view of a form of my device with the top plate removed so as to show the arrangement of pulleys. Fig. 2 is the front view of the same rheostat with the front plate removed. Fig. 3 is a cross-sectional view of Fig. 1 on the line A—A. Fig. 4 is a cross-sectional view of a form of self- 30 alining resistance elements which may be used in the rheostats. Fig. 5 is a cross-sectional view of a modification of the resistance element shown in Fig. 4. Fig. 6 is a cross-sectional view of another form of 35 self-alining resistance element. Fig. 7 shows the relative position of the grooves in the resistance element to the frame and compression member. Fig. 8 is a sectional end view of a modification taken on the line 40 B—B of Fig. 9. Fig. 9 is a partial cross-sectional view of the rheostat taken on the line C—C of Fig. 8. Fig. 10 is an enlarged view of a conducting plate used to connect two piles in series. Fig. 11 is an enlarged 45 view of a conducting plate used to connect two piles in parallel.

Referring to the rheostat shown in Figs. 1, 2, and 3, a plurality of resistance elements or plates 1 are arranged in a plurality of 50 piles 2. These piles rest on non-conducting

guide rods 3 which are supported between the parallel members 4, also of non-conducting material or conducting material properly insulated. The ends of the four members are joined by end plates 5. Top and 60 bottom plates 6 are preferably secured to the two inner members 4 to take the thrust from the piles. Between every other pile, threaded rods 7 are passed. At one end of each rod, pulley blocks 9 are attached to support 65 the pulleys 8. The compression members 10 fit loosely over the other ends of the rods 7 and are held in place by nuts 11. I have shown wheels 12 in the place of nuts 11 on certain of the rods to adjust the rheostat as 70 will be explained later. A cable 13 passes over pulleys 15 and 8, and the end 16 is attached to the frame 4 by the rod 7 and wheel 12. Pressure is uniformly transmitted through the various pulleys by a weight 14 75 attached to the other end of the cable. The weight may be varied so as to adjust the pressure as desired.

The conducting plates 17 are placed as 80 shown to connect the piles in series. Any number of piles, however, may be connected in parallel by appropriate plates. Binding posts 18 are provided for the terminals. A clamp 19 or other device is fastened to the member 6 so as to hold the weight end of 85 the cable when it is desired to compress the rheostat by hand wheel 12. In such case, the weight of course would have no effect.

Fig. 10 is an enlarged view of the conducting plate 17. This consists of a metal plate 90 having a notch 21 to fit over the rod 7 and preferably a lug 20 for grasping it to remove it.

Fig. 11, a similar plate having two notches 21 is made long enough to abut 95 against the ends of four piles. Two piles can thus be placed in parallel.

In Figs. 4, 5 and 6, three illustrative types of self-alining resistance elements adaptable for use in this rheostat are shown. Referring to Fig. 4, the resistance element has a series of parallel corrugations or grooves 22. The upper surface of the element is rounded at 23, the ridges 23 serving as contacts and fitting into the alining grooves 24 in the 100 adjacent plate.

In Fig. 5 the grooves are deeper at one end than at the other. The resistance elements would be arranged in the pile so that the cooling medium would enter at the shallow 110

end of the groove, *i. e.*, in Fig. 2 the shallow end would be at the bottom and in Fig. 8 it would be at the right.

In Fig. 6, a form of element is shown consisting of two differently shaped plates 26 and 27 which embody the same advantages as the elements shown in Figs. 4 and 5. In this figure, the grooves of 27 are made deeper than those of 26 to secure the alining and ventilation features.

In Fig. 7, an enlarged partial cross-section of two piles and the compression member 10 is shown in order to illustrate the direction of the corrugations in the rheostat in Figs. 1, 2, and 3. The frame 4 is insulated from the members 7, 9 and 16 as indicated in black in this figure.

In Figs. 8 and 9, the rheostat of Figs. 1, 2, and 3 has been turned to make a vertical instead of a horizontal type. Two vertical sides 28 and four members 4 form a frame for the rheostat. The guide rods 3 fit into the members 4 to support the resistance plates 2 in horizontal rows, the rows being arranged in a vertical column. Pressure is applied to the plates by the weight 14 through cable 13, and pulleys 15 and 8.

The resistor plates are placed in this type with the grooves horizontal. A baffle plate 29 seals the bottom of the space at the left of the column (Fig. 8) and a similar plate 30 seals the top of the space at the right. The cooling medium passes around and between the block as indicated by the arrows.

Instead of weights, a variable spring may be used to place tension on the cable 13. The tension on the cable 13 will tend to draw the pulleys 8 closer together, thus compressing the piles through rods 7 and members 10. It will be noted that the pull on the rods 7 is the same so that the compression in all the piles will be equal. By changing the tension on the cable 13 by any means, the compression of all the piles is simultaneously altered.

The current will pass through all of the piles in series on each side of the rheostat when the bridging members of Fig. 10 are placed as shown in Fig. 1. The two sides of the rheostat may be connected either in parallel or in series. The rheostat can be arranged so that two piles are in parallel throughout by using the bridging plate shown in Fig. 11. Similarly, three piles could be placed in parallel by using connectors spanning six piles. Piles connected in parallel will carry the same load, since they are all equally compressed.

The resistance of the bank of resistors may be adjusted by changing the weights previously described. When the weight is used, the compression is independent of the expansion or contraction due to change of temperature.

By locking the cable 13 by means of the

clamp 19, the action of the weight will be removed and the compression of the piles can be varied by means of any one of the hand wheels 12. The whole rheostat can thus be uniformly controlled at one point.

In Figs. 1 and 2, I have shown set screws 31 threaded into the member 4 to engage two of the rods. By tightening these set screws, the rods 7 and pulleys attached thereto will be held stationary. In this manner, the resistance of the piles controlled by the two rods may be regulated independently of the others by adjusting the hand wheels or nuts connected thereto. Similar screws of course can be used to hold any or all of the rods 7. Sometimes it is necessary to have a constant resistance with translating devices connected in shunt thereto. With my device the piles controlled by the rods held by the screws 31 may be connected for instance across the line and translating device may be tapped off of one of them, and the remaining ones may be connected in series therewith to regulate the current.

In the type of rheostat shown in Figs. 1, 2 and 3, the air will pass vertically through the grooves in the resistor plates and absorb the heat generated. The sides 5 of the rheostat extend above and below the piles and thus produce a chimney effect. These sides may be extended to any height desired.

The grooves in the back of the plates shown in Figs. 4 and 5 serve as means for keeping them in alinement; hence, no plates or rods are needed at the sides of the pile. This is an important feature as friction is thereby reduced which makes the pressure between all the blocks more uniform.

In the rheostat shown in Figs. 8 and 9, the arrangement of pulleys and weights is similar to that of Figs. 1, 2 and 3. Instead of arranging the plates with the grooves vertically so that the heated air from one plate would pass into the next they are placed with the grooves horizontal. A lower baffle 29 permits air to enter at one side only. A baffle 30 is placed diagonally opposite at the top and prevents the air from leaving at the same side on which it enters, thus forcing the air to pass horizontally through the grooves and between the piles, as shown by the arrows. The heated column of air in the rheostat will cause a considerable draft which will aid in the ventilation. Any of the plates shown in Figs. 4 and 5, and 6 could be used in this vertical type, with the same advantages as previously described.

The location of the weights and pulleys in the preceding figures is not by any means the only one which could be used. Many other variations of the arrangement may be readily devised. Likewise, other forms of plates and alining means could be used to accomplish the same results as those specifically shown.

Having described my invention, what I claim is:

1. In a compression rheostat, a plurality of piles, rods for transmitting pressure to said piles and flexible means coöperating with said rods to compress the piles.
2. In a compression rheostat, a plurality of piles, means for transmitting pressure thereto, and a flexible cable for applying force to said means.
3. In a compression rheostat, a plurality of resistance elements arranged in a plurality of piles, compression members, rods connected to said members, pulleys secured to the rods, and flexible means passing around the pulleys for compressing the piles.
4. In a compression rheostat, a plurality of resistance elements arranged in a plurality of piles, compression members and flexible means attached to the said compression members to simultaneously compress the piles.
5. A resistance element having a plurality of corrugations on one side and alining grooves on the other, said corrugations varying in depth from one end to the other.
6. A resistor having a plurality of corrugations, each of said corrugations varying in depth from one of its ends to the other.
7. A resistor having corrugations varying in depth from one of their ends to the other.
8. A corrugated resistor plate having the top of the ridges parallel to the plane of the base of the plate and having said corrugations of variable depth.
9. In a compression rheostat, resistor plates having upper and lower bounding planes, a plurality of adjacent grooves in each plane, the grooves in one plane varying in depth from one of their ends to the other, and the ridges in one plate adapted to fit into the grooves of the adjacent plate to aline the said plates.
10. In a compression rheostat a plurality of corrugated resistors, a plurality of piles consisting of said resistors arranged vertically, and means for admitting a cooling medium at one side only of the corrugations, and withdrawing it at the other side.
11. In a compression rheostat, a plurality of corrugated resistors having the corrugations in a horizontal direction, a plurality of piles consisting of said resistors arranged vertically, and means for admitting a cooling medium at one side only of the corrugations and withdrawing it at the other side.

In testimony whereof, I hereunto affix my signature.

EMERSON L. CLARK.
